TRIGGER ACTUATING MECHANISM

Warren L. Nahm, Oakland, and George W. Brown, San Francisco, Calif., assignors to Bankers Protection Co., San Francisco, Calif., a corporation of Nevada

Application March 14, 1932. Serial No. 598,634

11 Claims. (Cl. 42—69)

This invention relates to a trigger actuating mechanism particularly intended for use in connection with trigger actuated signaling devices, alarm devices, and the like, one application of the 5 invention being illustrated in a co-pending application filed by M. C. White and G. W. Brown, September 9th, 1931, Serial Number 561,980, entitled "Security bag".

The object of the present invention is to generally improve and simplify the construction and 10 operation of trigger actuating mechanisms; to provide a trigger actuating mechanism which is adapted to be either manually or mechanically actuated; to provide a trigger actuating mechanism which is automatically detached during actuation of the trigger; to provide a trigger actuating mechanism which can be extended any 15 distance desired for convenient or secret operation; to provide a trigger actuating mechanism whereby a lock may be actuated; and further, to provide a trigger actuating mechanism which can be readily and quickly connected with a trigger and rendered operable or inoperable as conditions may demand.

20 The trigger actuating mechanism is shown by way of illustration in the accompanying drawings, in which—

Fig. 1 is a side elevation in section of a security bag showing the application of the trigger actuating mechanism.

25 Fig. 2 is an enlarged longitudinal vertical sectional view of a firing head and a portion of a cartridge case attached thereto, said view also showing the trigger actuating mechanism whereby the firing head is actuated.

30 Fig. 3 is a side elevation of the housing in which the trigger actuating mechanism is mounted.

Fig. 4 is a perspective view of the trigger actuating arm.

Fig. 5 is a perspective view of a shutter arm.

Fig. 6 is a vertical cross section taken on line VI—VI of Fig. 3.

Fig. 7 is a longitudinal vertical section of a 45 portion of the frame members 5 and 5a of the bag, said section showing the application of an automatically actuated locking mechanism.

Fig. 8 is a vertical cross section taken on line VIII—VIII of Fig. 7.

50 Fig. 9 is an enlarged vertical section taken on line IX—IX of Fig. 7.

Referring to the drawings in detail and particularly Fig. 1, A indicates a hand-bag having a bottom portion 2, and end portions 3 and 4.

55 The upper portion of the bag is provided with a

pair of frames 5 which are pivotally connected at opposite ends as indicated at 6 to permit the bag to be opened and closed. A suitable lock, hereinafter to be described, is provided and handles, such as indicated at 7, to permit the bag to be readily carried.

Formed interiorly of the bag and in one side thereof is a pocket generally indicated at B. This pocket forms a receptacle for a firing head C and a cartridge case D. The lower end of the 65 pocket is open and so is the registering portion of the bottom 2 of the bag so as to permit the cartridge case to be inserted or removed and also to permit shots and smoke to be discharged through the bottom of the bag, as will herein- 70 after be described.

The firing head C container contains a trigger 9, firing pins on a lever 10 pivotally mounted in the head, as indicated at 11, and it further contains a spring 12 and a series of connected links 75 E which are tripped by the trigger and through which movement is imparted to actuate the firing pins. The trigger 9 is, in this instance, operated through means of a trigger actuating mechanism generally indicated at F. This mechanism consists of a pull wire 14a having a loop 14 formed at one end. The pull wire is attached to a pivoted arm 40 and this is connected with trigger 9 through means of a wire 43.

The bag illustrated in Fig. 1 is known as a 85 security bag and is particularly intended for the transfer of money and other valuables from one bank or place of business to another. Messengers carrying valuables are from time to time stopped or interfered with by holdup men and the like, 90 and the purpose of the invention is that of protecting the messenger, and secondly, in providing means for detecting or tracing the whereabouts of the holdup man after the bag has been taken from or surrendered by the messenger.

The messenger equipped with a bag of this character carries the bag by means of the handles 7 and one finger is inserted through the loop 14 of the pull wire which actuates the trigger actuating mechanism generally indicated at F. If 100 the messenger is held up, his instructions from his employer require him to freely hand the bag to the holdup man, but in so doing, he retains the loop 14 of the pull wire about his finger, thus in handing the bag to the holdup man he actuates the trigger actuating mechanism and this in turn exerts a pull on the trigger 9. When this is pulled the trigger mechanism is tripped causing firing of the percussion caps indicated at 15. These 105 ignite a quick burning fuse indicated at 16 and 110

this in turn ignites fuses, such as shown at 17 and 18, the fuses 17 igniting charges of explosive which fires a succession of shots and the fuses 18 igniting smoke ejecting charges. Hence, if the bag is handed over to a holdup man the trigger is released during the transfer of the bag without the holdup man being aware of the fact. The quick burning fuse is ignited and this ignites the slow burning fuses 17 and 18, hence the holdup man will have an opportunity to get away or, at least, think that he is getting away with the bag before he is alarmed by the firing of the shots and the discharge of dense volumes of smoke from the bottom of the bag. In most instances, it is very likely that a holdup man will drop the bag and attempt to escape, but if he does not do so, his whereabouts can easily be traced due to the dense volumes of smoke discharging.

A brief description of the mechanism contained in the firing head and the construction of the cartridge case is submitted in this instance as this forms no part of the present application. Furthermore, this part of the mechanism is described in complete detail in a co-pending application entitled "Firing mechanism", filed November 30th, 1931, Serial Number 577,994.

The trigger actuating mechanism consists of a housing generally indicated at F. It is provided with two side walls 20 and 21, a connecting bottom section 22, and a side flange 23 whereby it is riveted or otherwise secured to one of the frames 5 or the interior surface of the bag as shown in Fig. 1. The upper portion of the housing is open as indicated at 24 and a second opening is formed in the bottom portion of the housing as indicated at 25. This opening is, however, normally maintained closed by means of a shutter arm generally indicated at 26. This shutter consists of two arms, see Fig. 5, and a connecting bottom section on which is formed a projection 27 adapted to be engaged by the finger to impart movement to the shutter. The shutter is pivotally mounted on a pin 28 extending through the housing and it is normally held in the position shown in Fig. 3 by means of a spring 29, one end of the spring engaging the shutter while the other end engages the housing. The function of the shutter will hereinafter be described. Pivotally mounted on the shaft 28 within the housing is a trigger actuating arm such as shown at 40 in Figs. 2 and 4. The lower end of the arm is provided with an open ended slot 41 and the opposite side is provided with perforated lugs 42 to which a wire or cable 43 is attached. This wire passes through a tube or the like which is connected with a firing head and the opposite end of the wire is connected with the trigger 9 as shown in Fig. 2. A pull wire 14a having a loop 14 at one end and a bead or a head member 14b at the opposite end is employed. The bead is inserted in the open ended slot 41 and when a pull is exerted on the wire 14a through means of the loop 14, arm 40 will swing about the pivot 28 in the direction of arrow a and will finally assume the dotted line position indicated at 40a. In this position the head end of the wire pulls out of the slot 41 and the pull wire is thus released with relation to the trigger actuating arm and will be retained by the messenger as it is attached to one of his fingers. The feature of having a trigger actuating mechanism, a portion of which is detachable or releasable, is important as when the bag is handed by the messenger to the holdup man it is essential that the trigger mechanism shall be actuated and in such a manner that the

attention of the holdup man is not attracted. If the pull wire was not releasable it might be difficult for the messenger to transfer the bag and at the same time pull the trigger but, in this instance, it is accomplished without attracting any attention as the pull wire is retained on the finger and falls directly into the hand of the messenger when the bag is handed over and is thus not only hidden from view but is, furthermore, substantially noiseless in operation.

The trigger actuating mechanism here shown may be rendered operative or inoperative as desired. If the pull wire is detached the mechanism is rendered inoperative as there is no way of reaching the trigger actuating arm 40. On the other hand, if the pull wire is attached as shown in Fig. 2, the trigger actuating device is operative and will exert a pull on the trigger the moment a pull is exerted on the wire 14a. Hence, the pull wire is only attached when the messenger is going to carry the security bag from one place to another and it should be detached the moment the bag is delivered, and similarly, it should be detached when the bag is not in use so as to prevent other employees from tampering with the bag and accidentally setting off the firing mechanism.

In order that the pull wire may be readily attached or detached the shutter 26 is employed. The shutter is pulled rearwardly in the direction of arrow b and as such uncovers the lower opening 25. The beaded end of the pull wire is then inserted through the upper opening 14c and pushed downwardly through the housing F where it will finally pass out through the opening 25. The messenger then takes the beaded end of the pull wire and pushes it into the open ended slot 41 of the trigger actuating arm 40 and then releases the shutter which swings back due to spring action. The moment the shutter closes, the beaded end of the pull wire will be retained as there is not sufficient space between the end of the trigger actuating arm and the curved bottom of the housing F to permit it to be detached. On the other hand, it is automatically detached when the trigger actuating arm 40 reaches horizontal position as clearance is provided at that point between the slotted end of the arm 40 and the housing to permit the beaded end of the wire to be pulled out of the slot. Furthermore, it will be noted that the end of the arm 40 is slightly bent, see Fig. 4, so as to assist in releasing the beaded end of the pull wire when it reaches the point where it should be released.

Where a mechanism of this character is attached to a security bag, such as shown in Fig. 1, it is often desirable to automatically lock the bag to prevent the robber from opening the bag, removing the contents and then leaving the bag at the scene of the robbery or in the immediate vicinity. In fact, if a robber could immediately open the bag and remove the contents quickly, it is possible that he could get away before any audible or visible signal or alarm is given and to that extent partially defeat the purpose or protection sought. A modified form of the invention embodying a locking mechanism operable through means of the trigger actuating mechanism is, accordingly, shown in Figs. 7 to 9.

In this instance, housing F is provided with an extension 50 in which is slidably mounted a locking bolt 51. The bolt is provided with a collar 52 and a spring 53 is interposed between the collar and one end of the extension 50. When the bolt is retracted, that is, to assume unlocked po-

sition, spring 53 is placed under compression and, as such, will project the bolt to locking position when this is released. One end of the bolt is provided with a notch 54 and this is normally engaged by a latch 55, see Figs. 7 and 8. The latch is pivotally mounted at 56 and it is provided with a tripping arm 57 which lies in the path of the arm 40 to which the pull wire 14a is connected. A spring 58 is interposed between the latch arm 10 and the housing 50 so as to normally secure the latch in locking position with relation to the locked bolt, but when the trip arm 57 is engaged the latch is swung about its pivot 56 and the bolt is released and, when it is released, spring 53 will project the bolt into locking position.

Before proceeding further with the description, it should be stated that the security bag is provided with a pair of frame members 5 and 5a which are pivotally connected at 6, see Figs. 1 20 and 9. The housing 22, together with the extension 50 formed thereon, is riveted, or otherwise secured, to the inner frame member 5a while the outer frame has secured thereto by means of a rivet 59 and S-shaped locking member 60. When 25 the bag is closed the lower end of the S-shaped member enters the outer end of the housing extension 50 and as such lies in the path of the locking bolt 51, and when the locking bolt is released, it passes in front of the S-shaped member, as shown in Fig. 9, and as such locks or secures the frame members 5 and 5a against being opened.

In actual operation, if the pull wire 14a is pulled by means of the loop 14, arm 40 will swing 35 about its pivot 28 and as such will not only actuate the trigger 9 but it will also engage the trip arm 57 of the latch 55, thus swinging the latch about its pivot 56 to a position where it will move out of the notch 54 and thus release the locking bolt 51. This, when released, is propelled forwardly by the spring 53, which has previously 40 been placed under compression, and the forward end of the bolt 51 will, accordingly, engage the cooperating locking member 60 and thus secure 45 the bag against being opened, hence preventing a holdup man from opening the bag and removing the contents, as previously described.

Another important feature of the present invention is the provision of a lock which can not 50 be opened by a key mechanism of any character whatsoever, as the locking mechanism constructed as here shown can only be released by drilling, cutting, or otherwise removing the rivet 59, which secures the cooperating locking member 60. Hence, if the bag has been locked accidentally, or otherwise, it is necessary to bring the bag to a shop or to a person equipped with the proper tools so that the rivet 59 may be removed. After it has been removed the bag may 55 be opened and the bolt may be returned to released position and latched by the latch 55. The cooperating locking member 60 may then be reinserted and fastened with a new rivet and the bag is again ready for use and operation. Obviously, a holdup man can not take the time to cut 60 away or drill the rivet 59 as the time it would require would be too great, that is, the visual and audible alarm mechanism would take effect before work of this kind could be accomplished 65 and removing of the rivet by the holdup man would accordingly be prevented.

While the trigger actuating mechanism is particularly intended for use in connection with a security bag such as here illustrated, it is obvious 70 that it may be otherwise applied. For in-

stance, a device of this character may be installed in a home as a burglar alarm. In that case, the wire 14a may be attached to a door, a window, or the like, and when these are opened a pull will be exerted on the pull wire. During such opening the trigger would be pulled and before the burglar could really become active shots would be fired and smoke would commence to discharge, thus frightening the burglar and at the same time awakening the occupants of the house. If a police officer should happen to be on the same street it is possible that it would aid him in catching the burglar as the smoke would indicate to the officer that an attempt had been made to rob the house and, if he saw any one walking or running away from the house, he could be fairly certain that that person was the burglar.

The device could be attached to an automobile. For instance, the pull wire would be attached to any movable part of the automobile so that if an unauthorized person attempted to drive away, the trigger would be pulled and thereby trip the firing mechanism. Hence, it will be understood that the pull wire may be either manually or 95 mechanically actuated as desired.

While certain features of the present invention are more or less specifically described, we 100 wish it understood that various changes may be resorted to within the scope of the appended 105 claims. Similarly, that the materials and finish of the several parts employed may be such as the manufacturer may decide, or varying conditions or uses may demand.

Having thus described our invention, what we 110 claim and desire to secure by Letters Patent is—

1. In a device having a trigger mechanism an actuator for said mechanism comprising a member consisting of two sections upon which a pull is exerted when actuating the actuator, and 115 means whereby one section is automatically detached from the device when the members have moved a predetermined distance while a pull is exerted.

2. An actuator of the character described comprising a housing, a movable member in the housing, an actuator detachably connected with the movable member, and means for automatically releasing the actuator whereby it may be pulled free of the housing when the movable member 125 has been actuated.

3. An actuator of the character described comprising a housing, a pivoted member in the housing, an actuator detachably connected with the pivoted member, and means for automatically 130 releasing the actuator during swinging movement of the pivoted member whereby it may be pulled free of the housing.

4. An actuator of the character described comprising a housing, a pivoted member in the housing, an actuator detachably connected with the pivoted member, and means for automatically releasing the actuator when the pivoted member has swung a predetermined distance about its pivot whereby the actuator may be pulled free 140 of the housing.

5. An actuator of the character described comprising a housing, an arm pivotally mounted in the housing, said arm having an open ended slot formed in its free swinging end, a pull wire, and 145 a head member on one end of the pull wire insertable in the slotted end of the arm, said arm and housing being so positioned that the pull wire will be automatically released therefrom during swinging movement of the arm.

6. An actuator of the character described comprising a housing, an arm pivotally mounted in the housing, said arm having an open ended slot formed in its free swinging end, a pull wire, a head member on one end of the pull wire insertable in the slotted end of the arm, and means in the housing maintaining engagement between the headed end of the pull wire and the slotted end of the arm, said means releasing the beaded end of the pull wire when the arm has been swung about its pivot to a predetermined position.

7. The combination with a trigger actuated mechanism, of a trigger actuator, and a detachable member on the actuator releasable from the mechanism upon actuation of the trigger.

8. The combination with a trigger actuated mechanism, of a trigger actuator, a detachable member on the actuator, and means for automatically releasing said detachable member upon actuation of the trigger whereby said member may be pulled free of the mechanism.
